Inventor

Addison C. Fletcher

United States Patent Office.

ADDISON C. FLETCHER, OF NEW YORK, N. Y.

Letters Patent No. 61,615, dated January 29, 1867.

IMPROVEMENT IN GRATE BARS.

The Schedule referred to in these Letters Patent and making part of the same.

TO ALL WHOM IT MAY CONCERN:

Be it known that I, ADDISON C. FLETCHER, of the city, county, and State of New York, have invented a new and useful Improvement in Grate Bars; and I do hereby declare that the following is a full, clear, and exact description of the same, reference being had to the accompanying drawings, forming part of this specification, in which—

Figure 1 is a side view of a grate bar with my improvement.

Figure 2 is a longitudinal vertical section of the same.

Figure 3 is a plan of the same.

Figure 4 is a vertical section of the same.

Figure 5 is a vertical section of the fire-place of a cylinder boiler, illustrating the application of the grate bar.

Figure 6 is a vertical section, illustrating the application of the invention to a cylinder stove.

Figure 7 is a vertical section illustrating the application of the invention to an open fire-place for houses.

Similar letters of reference indicate corresponding parts in the several figures.

This invention consists in an improvement in the step-formed grate bar, which is the subject-matter of an application for Letters Patent, allowed January 31, 1866, the object of such improvement being to increase the efficiency and durability of such a bar, or of a grate formed of such bars.

The only parts of the bar, the construction of which differs in any essential respect from that of the bar represented and described in my above-mentioned former application, are the transversely arranged webs, *a a*, by which the several steps *A A* of the bar are connected. These webs, instead of being vertical, are sloping so as to give their faces an upward inclination, as shown in figs. 1 and 2, and they are faced with slabs of fire-brick, soap-stone, or other refractory material, *b b*. The faces of the said webs *a a* may be perforated in any suitable manner, but I prefer to make them with horizontal slots, *e e*, and grooves, *d d*, as shown in fig. 4, in which one of the facing slabs *b* is omitted to expose the web to view. The facing slabs *b b* have numerous perforations, *g g*, arranged in any suitable manner opposite to the slots and grooves of the webs, and are secured to the said webs partly by half dove-tail flanges, *c c*, at the tops of the webs, and partly by bolts, *f f*, passing through the slabs and webs and fitted with nuts at the backs of the webs. The perforations *g g* and slots *e e*, are perpendicular to the faces of the slabs *b b* and webs *a a*, and hence, as the faces of the said webs and slabs have an upward inclination, the jets of air admitted through the said perforations are delivered in an oblique upward direction, whereby they are caused to mix more intimately with the combustible gases illuminated from the fuel on the steps *A A*, than when delivered in a horizontal direction, as they are through the perforations of the vertical webs, and hence a more perfect combustion of these gases is effected, and a greater length of flame is obtained by my improvement. The facing slabs of refractory material protect the faces of the webs *a a* from the intense heat of the fuel in contiguity to the webs, and hence render the grate bars less liable to burn out in those parts, and more durable.

What I claim as my invention, and desire to secure by Letters Patent, is—

1. The arrangement of the connecting webs *a*, of the steps in a step-formed grate bar, in inclined or sloping positions, substantially as and for the purpose herein described.

2. The facing slabs *b b*, of refractory material, in combination with the connecting webs of the steps of a step-formed grate bar, substantially as and for the purpose herein specified.

ADDISON C. FLETCHER.
